[57] **CLAIM**

The ornamental design for a hose reel, as shown and described.

DESCRIPTION

FIG. 1 is a partial right side, partial top and rear perspective view of a hose reel showing my new design; FIGS. 2 and 3 are respectively front and rear elevational views thereof;

FIGS. 4 and 5 are respectively right and left side elevational views thereof; and

FIGS. 6 and 7 are respectively top and bottom plan views, with the handle rotated 180° from its FIG. 1 position.

FIG 1

FIG 2

FIG 3

FIG 4

FIG 5

FIG 6
